UNITED STATES PATENT OFFICE.

FRANK C. MOCK, OF CHICAGO, ILLINOIS, ASSIGNOR TO STROMBERG MOTOR DEVICES CO., OF CHICAGO, ILLINOIS, A CORPORATION OF ILLINOIS.

AIRPLANE CARBURETOR.

Application filed January 16, 1924. Serial No. 686,474.

My invention relates to carburetors, particularly to airplane carburetors or others in which there is a plurality of carburetor barrels or mixture outlets each controlled by a throttle valve. The invention is applicable where a number of individual carburetors are provided to serve an engine or where a carburetor structure is provided having a number of barrels each connected 10 to serve one or more of the engine cylinders. Under such conditions of operation it is very desirable that the throttle valves be closely fitted and operate in close synchronism, because if the throttle valve for one set of 15 cylinders be wider open than the throttle valve for another set, it will cause the former set of cylinders to speed up the motor and over-run the other.

During idling the manifold pressure is 20 generally less than .52 of atmospheric pressure and consequently the rate of air flowing past the throttle is the atmospheric velocity of sound and is independent of changes in engine speed or manifold vacuum so long 25 as this manifold pressure is less than .52 of the atmospheric pressure. This means that the air flow through the throttle crack is independent of the engine speed, and if the engine is caused to speed up to 600 R. 30 P. M. by one throttle being unduly open while the remaining throttle or throttles are at a position corresponding to 300 R. P. M., these remaining cylinders will receive an air charge only one-half that of normal 35 idling, under which condition their charges will either not ignite at all, or will burn so slowly that flame will be thrown out of the cylinders when the exhaust valves open.

The object of my invention is, therefore, 40 to provide simple and efficient means for insuring accurate synchronous adjustment of the throttle valve.

On the drawings:—

Figure 1 is a plan view of a double barrel carburetor;

Fig. 2 is a sectional view on plane 2—2 of Fig. 1 of the upper part of one barrel;

Fig. 3 is a detail elevational view of the sector gears connecting the throttle shafts; 50 and

Fig. 4 is a detail sectional view of one of the gears, illustrating its eccentric mounting on the throttle shaft.

On the drawings, 10 represents the body 55 of the carburetor structure which has the

two carburetor barrels 11 and 12 provided, respectively, with the throttle valves 13 and 14. The valve 13 is secured on the shaft 15 extending diametrically through the barrel 11 and the valve 14 is secured on the shaft 16 extended diametrically through the barrel 12 and parallel to the shaft 15.

It is first necessary that an adjustment be provided so that the throttles can seat at the same time regardless of small inaccuracies of the connecting means for transmitting operative motion from one throttle to the other. In the present instance this motion transmitting means comprises a gear sector 17 on throttle shaft 15 and a companion gear sector 18 on the throttle shaft 16. Each gear is formed with a split hub 19 adapted to be clamped to its shaft by a screw or bolt 20. These split hub mountings of the sector gears permit of easy adjustment of the gears on their respective throttle shafts so that both throttles can be readily adjusted to seat at the same time. The percentage of variation in mixture flow between the two carburetor barrels as a result of mechanical inaccuracies is greater at small throttle openings than at large, and it is therefore desirable during small throttle openings that the two throttles follow each other in very close synchronism. I have 75 therefore arranged that during small throttle openings the sector gears 17 and 18 transmit a fine control between the throttles by virtue of a close mesh between the gears. I have found, however, that if these gears 80 are meshed tight enough to give the requisite fine control at small throttle openings, they are very apt to stick or jam at other throttle openings. In addition, this fine control is 85 very difficult to achieve in ordinary methods of manufacture. To avoid these difficulties I have interposed between one of the sector gears, such as the gear 17, and its respective throttle shaft 15, an eccentric bushing which 90 permits of fine adjustment of the two gears to the end of obtaining a close accurate mesh during the low idling positions, and a looser mesh during the relatively wide openings of the throttles. This eccentric bushing is indicated at 21 and has an outer hexagonal 95 head 22, by which it may be readily rotated in the split hub of the gear. The eccentric bushing and its hexagonal end 22 are 100 also split so that the clamping pressure exerted by the hub 19 will clamp the eccen- 105 tric bushing 21. The eccentric bushing 21 is 110 secured to the split hub 19 by a screw 23.

tric in the gear to the throttle shaft 15. It will be apparent that by slight rotation of this eccentric bushing the sector gear 17 can be adjusted so that it will have a very close mesh with the other gear 18 during low idling positions of the throttle, and a relatively looser mesh during open positions of the throttles. On twelve cylinder motors where several carburetors are employed, smooth operation of the motor at low speeds can only be secured with the utmost accuracy in the fit of the carburetor throttles and in the relative synchronization with each other. I have found that if the gear sectors have any tendency to stick or move hard in certain positions, the operating rods and levers inevitably twist or slip slightly so that this synchronization cannot be maintained, and it is a pronounced advantage to have the eccentric adjustability of the gears, as above described, so that they can be set to move freely and not bind in any position.

As shown in Fig. 1, the throttle shaft 15 of the throttle valve 13 is extended beyond the carburetor barrel and the sector gear respectively, and is provided with knurled ends 23 upon which are adapted to be mounted the manual control lever and the control lever for linking together two of such carburetors, if two are employed. The other throttle shaft extends through a hard metal bushing 24 in the rear wall of the carburetor barrel and is threaded for receiving a cap 25. The inner face of this cap is recessed to receive a compression spring 26 which bears against the end of the bushing 24 and places an end thrust on the throttle shaft to hold it firmly against vibration.

I thus provide simple and efficient means for insuring easy, smooth and synchronous operation of the throttle valve and I claim as follows:—

1. In a carburetor, the combination of a pair of carburetor barrels, individual throttles in each of said barrels, gears operatively connecting said throttles, and eccentric means for adjusting the mesh between said gears.

2. In a carburetor, the combination of a pair of carburetor barrels, individual throttles in each of said barrels, and gears connecting said throttles, said gears being arranged for a relatively tight mesh in one position of said throttles and a relatively

looser mesh in another position of said throttles.

3. In a carburetor, the combination of a pair of carburetor barrels, individual throttle valves in each of said barrels, individual shafts for operation of said throttles, gears on each of said shafts meshing together, and an eccentric between one of said gears and its shaft for adjusting the mesh between said gears.

4. In a carburetor, the combination of a pair of carburetor barrels, individual throttles for said barrels, gears connected to said throttles, and means for causing said gears to mesh closer as the valves are moved towards closing position and to mesh looser as the valves are moved toward opening position.

5. In a carburetor, the combination of a plurality of carburetor barrels, a throttle valve in each barrel, a shaft for each valve, said shafts being parallel, gears connecting between said shafts and operable to cause simultaneous movement of said throttle valves, and means for causing the gear axes to move closer together when said throttle valves are moved to one position.

6. In a carburetor, the combination of a pair of carburetor barrels, a throttle valve in each barrel, a shaft for each throttle valve, said shafts being parallel, intermeshing gears connecting said shafts, and means for causing the gear axes to move closer together when said gears are operated to move said valve to closing position.

7. In a carburetor, the combination of a pair of carburetor barrels, a throttle valve for each barrel, a shaft for each throttle valve, said shafts being parallel, a gear train between said shafts, and means for gradually reducing lost motion between the gears of said train when said train is operated to move the valves to closed position.

8. In a carburetor, the combination of a pair of carburetor barrels, a throttle valve in each barrel, a supporting shaft for each valve, gears connecting said shafts, and means for causing said gears to move gradually into closer mesh as the valves move to idling position.

In witness whereof, I hereunto subscribe my name this 5th day of January, 1924.

FRANK C. MOOK.
